CLAIM

I claim the ornamental design for a battery, as shown and described.

DESCRIPTION

FIG. 1 is a perspective view of a battery showing the new design;

FIG. 2 is a front view of a battery thereof;

FIG. 3 is a back view of a battery thereof;

FIG. 4 is a left side view of a battery thereof;

FIG. 5 is a right side view of a battery thereof;

FIG. 6 is a top plan view of a battery thereof; and,

FIG. 7 is a bottom view of a battery thereof.

1 Claim, 7 Drawing Sheets
